(No Model.)

J. DUFFY.

SPINDLE SUPPORTING AND DRIVING DEVICE FOR SPINNING FRAMES.

No. 445,500.

Patented Jan. 27, 1891.

UNITED STATES PATENT OFFICE.

JOSEPH DUFFY, OF PATERSON, NEW JERSEY.

SPINDLE SUPPORTING AND DRIVING DEVICE FOR SPINNING-FRAMES.

SPECIFICATION forming part of Letters Patent No. 445,500, dated January 27, 1891.

Application filed June 11, 1890. Serial No. 355,065. (No model.)

To all whom it may concern:

Be it known that I, JOSEPH DUFFY, of Paterson, in the county of Passaic and State of New Jersey, have invented a new and useful Improvement in Spindle Supporting and Driving Devices for Spinning-Frames, of which the following is a full, clear, and exact description.

My invention relates to improvements in oscillating bolsters for carrying the spindles of spinning-frames; and the object of my invention is to produce a bolster by means of which the spindles may be held so that they may be conveniently operated by a belt traveling across the frame of the machine, and also to provide means for maintaining a uniform tension on the bolsters and spindles; and to this end my invention consists in certain features of construction and combination of parts, which will be hereinafter described and claimed.

Reference is to be had to the accompanying drawings, forming a part of this specification, in which similar letters of reference indicate corresponding parts in both figures.

Figure 1 is a broken plan view showing the manner in which the bolster and the spindles mounted therein are located with reference to the belt; and Fig. 2 is a broken vertical view, partly in section, showing the construction of the bolster, the manner in which it is mounted, and the manner in which the spindles are mounted therein.

The spindles A are of the usual construction, and are mounted vertically in the arms B' of the bolster B, said spindles having a projecting lower end A' mounted in suitable bearings in the arms, and having the extreme lower ends formed into pivots a, adapted to rest in corresponding sockets in the bolster-arms. The bolster B has a horizontal body portion, to the outer ends of which are fixed the vertical arms B', which carry the spindles A, as described, and the bolster has fixed to its under side a depending trunnion B², which turns in suitable bearings C' in the rail C of the spinning-frame. The arms B' of the frame have an enlarged recess b, which serves as an oil-conductor to the foot of the spindle, a portion b' near the top adapted to serve as a bearing for the spindle, and a socket b² be-

neath the recess b, adapted to receive the pivot a at the foot of the spindle. The trunnion B² of the bolster has a depending portion B³ projecting through the frame and provided with a suitable nut b³, and mounted upon said projecting portion is a spiral spring D, one end of which presses against the nut b³ and the other against a washer c at the lower end of the bearing C'. The spring will thus give the necessary tension to the bolster. A suitable washer d, preferably of felt, is placed between the upper end of the bearing C' and the body of the bolster.

Upon the upper side of the bolster is a boss B⁴, having a suitable cover B⁵, and having a vertical bore b⁴ therein, said bore opening into the horizontal bore b⁵, which extends across the body of the bolster and enters the recesses b in the arms B'. It will thus be seen that by removing the cover B⁵ oil may be poured in the bore b⁴, and will flow through the bore b⁵ to the recesses b, and thus lubricate the lower bearings of the spindles. The arms B' of the body of the bolster extend through openings c' in the frame-rail C, said openings being somewhat larger than the diameter of the arms B' to permit the necessary lateral movement of the bolster-arms.

Fixed to the spindles A are suitable whirls E, said whirls being hollow, as shown in Fig. 2, to enable them to fit over the upper ends of the arms B', and having upon their lower portions laterally-extending flanges E', adapted to support a belt. The belt F, by which the whirls and spindles are rotated, extends over suitable horizontally-rotating pulleys H, power being taken from a convenient shaft. The spindles are arranged in the frame in relation to the belt F so that the belt will press firmly against the whirls E, so that as the belt is moved the motion will be transmitted to the whirls and thence to the spindles. It will be seen that as the tension of the belt tends to press one whirl out and the trunnion B² being oscillated the opposite whirl on the bolster will be moved inward, so that there will be an even pressure upon both whirls of a bolster, thereby imparting the same speed to each spindle, and consequently the same twist to the yarns, and as the various bolsters have each the same relation to the belt all

are driven at the same speed, thereby imparting an even twist to all the yarns spun.

In running the spindles from continuous belts instead of separate bands it has been 5 the practice to have a pulley H for every four spindles, there being two spindles on opposite sides of the pulley; but by means of my invention it will be seen that the capacity of each pulley is doubled, as each pulley drives 10 eight spindles, the oscillating bolster causing the two spindles it carries to bear with an even pressure upon the belt, as described.

I do not confine myself to the particular construction of the bolster, as it may be made 15 in as many parts as desired, and its construction may be varied to suit the taste of the maker.

Having thus described my invention, I claim as new and desire to secure by Letters 20 Patent—

1. The combination, with the frame of a spinning-machine and with a horizontally-moving belt arranged across the frame, of an oscillating bolster having a suitable trunnion 25 mounted in a bearing in the frame, said trunnion having a downwardly-projecting end carrying a suitable tension-spring and vertical arms fixed to opposite sides of the bolster, and spindles mounted in said arms, 30 said spindles having suitable whisks attached

thereto adapted to press against the belt, substantially as described.

2. The combination, with the frame of a spinning-machine and an endless belt moving horizontally across the frame, of an oscillating bolster pivoted in the frame, said bolster having vertical arms upon opposite sides, each provided with an enlarged recess, as shown, a horizontal bore extending through the body of the bolster from one arm to the other, a vertical bore opening from said horizontal bore through the top of the bolster, and spindles mounted in the bolster-arms, said spindles having whisks fixed thereto adapted to press against the belt, substantially as described.

3. A bolster for spinning-frames, consisting of a body having arms provided with bearings for the spindles, a central pivot, and oil-passages extending through the body to the 45 arm-bearings, substantially as described.

4. A bolster for spinning-frames, consisting of a body having arms provided with bearings for the spindles, and a central trunnion having a reduced end provided with a nut to 50 retain a spring, substantially as described.

JOSEPH DUFFY.
